UNITED STATES PATENT OFFICE.

BENJAMIN E. GETZ, OF MORTON, ILLINOIS, ASSIGNOR, BY MESNE ASSIGNMENTS, OF ONE-HALF TO GETZ POWER WASHER CO., OF MORTON, ILLINOIS, A CORPORATION OF ILLINOIS, AND ONE-HALF TO WESTINGHOUSE ELECTRIC & MANUFACTURING COMPANY, OF EAST PITTSBURGH, PENNSYLVANIA, A CORPORATION OF PENNSYLVANIA.

WASHING MACHINE.

REISSUED

Application filed April 14, 1923. Serial No. 631,965.

This invention has reference to washing machines, and particularly to that type including a clothes container or tub which is mounted for movement in the frame of the machine. In its preferred form the tub is mounted to be oscillated; however, one complete revolution is given the tub before it is reversed and oscillated in the opposite direction. This type of tub is usually in the form of a cylinder and known as an alternating rotary machine. While the mechanism is arranged to impart one complete revolution to the tub before being reversed, those skilled in the art will understand that the operating means may be arranged and constructed so as to give more or less than one complete revolution to the tub.

The invention has for its principal object to provide a controllable means for the tub or cylinder moving means; such controllable means movable to different positions and adapted in one of its positions to impart movement to the tub and in another of its positions adapted to restore the tub to normal stopped position without stopping the movement of the tub moving means.

The invention has for a further object to provide a controllable means for the tub moving means which is adapted to give to the tub a variable movement, such movement being under the full control of an attendant and being dependent on the position to which the controllable means is adjusted. In one position of the controllable means movement may be imparted to the tub, in another position of the controllable means the tub is restored to its normal stopped position, a variable movement being imparted to the tub as the controllable means is moved or held between such two described positions.

The invention herein described and shown is an improvement on the generic idea disclosed in the application of Thomas Littwiller and John Leader bearing Serial No. 442,336 (Letters Patent No. 1,460,203 dated June 26, 1923), and as to such generic disclosure a disclaimer is here made. Furthermore, this application is a companion to an application filed of even date herewith, bearing Serial No. 631,965. In said companion application the mechanism is shown

applied to an "oscillatory" tub, whereas in this case there is disclosed an "alternating rotary" tub, as distinguished from a tub which is oscillated less than one complete revolution, as is the case in the usual cylinder machine.

The present improvement resides in the controllable means which is applicable to a cylinder and adapted to impart an alternating rotary movement thereto, and in the inclusion of means for holding the controllable means in selective positions between its two extreme movements, whereby variable movement may be imparted to the cylinder, at the will of the operator or attendant.

That the invention may be more fully understood, reference is had to the accompanying drawings, forming part of the description, and illustrating a preferred embodiment of the invention, in which:—

Figure 1 is a side elevation of my controllable means for washing machines, and operating connections between the same and a power means, the frame supporting structure of the machine and cylinder being shown in dotted lines, with the cylinder in normal or neutral position, and dotted lines being used to illustrate movements of operating parts;

Figure 2 is a view somewhat similar to Figure 1, the relation of the controllable means and operating parts being the same, full and dotted lines indicating the movement of the parts to impart alternate rotary movement to the cylinder;

Figure 3 is a view somewhat similar to Figure 2, except that the controllable means has been moved from an operative to an inoperative position and the tub brought to normal position and stopped, without stopping the operating means, and

Figure 4 is a detail showing a means which is employed to stop and hold the controllable means at different points between the extreme and predetermined points to which the controllable means may be moved, whereby variable movement of the cylinder is obtained.

Like characters of reference denote corresponding parts throughout the figures.

Inasmuch as I am not concerned about the particular design or character of the ma-

chine, or the cylinder or tub mounted for movement therein, I have elected to show in dotted outline only, such parts.

Such a machine frame would include a suitable base 1, side members 2 and a top or cover 3. The tub 4 is here shown as an alternating rotary cylinder with a removable lid or section 5 for the insertion of clothes or fabrics into the cylinder and the removal of the same therefrom. As a mounting for the cylinder and operative parts frames 6 and 7 are provided. As the invention is applicable to nearly, if not all, cylinder machines it is apparent the machine shown is for illustrative purposes only, and although shown without a casing or cabinet, such could be employed if desirable.

In Figure 3, the cylinder or tub has been restored to its normal position, or as some would say, returned to its neutral position, and stopped, the operating means continuing in operation, and the controllable means idling and without imparting movement to or disturbing the cylinder or tub. In Figures 1 and 2 the controllable means has been moved to a position which will cause the operating means to impart movement through the controllable means to the cylinder or tub, and as a result the cylinder or tub is alternately rotated, first in one direction then in an opposite direction, somewhat as indicated by the full and dotted lines in Figure 2.

By "normal" or "neutral" position of the cylinder or tub, it is to be understood that that is the position the tub occupies when it is stopped (Figure 3) so that the lid or cover 5 thereof may be removed by an attendant to permit the removal of clothes or fabrics from the cylinder or tub and the placing of other articles or materials therein. Also, by the use of the word "restore" I mean the bringing back or righting of the cylinder or tub to "normal" or "neutral" position at the same time that the operating means is made ineffective so far as moving the cylinder or tub is concerned, yet without disturbing the movement of the operating means.

I am aware that the patent art discloses various mechanisms for stopping and locking and holding a tub in neutral position. One, in which it is necessary to return the tub to its neutral position, by hand, after it is stopped and then lock it. And others which require the manual operation and adjustment of a certain part or parts which are subsequently actuated to release a clutch or equivalent means to stop the movement of the tub when it reaches its neutral position. My controllable means when moved to one of its predetermined positions not only positively returns the cylinder or tub to its neutral position but stops it and holds it in such position, and the operating means can continue in operation. When the controllable means is moved to its other predetermined

position the cylinder or tub is simultaneously and automatically released permitting it to be rotated by the operating means through such controllable means.

8 designates a driving shaft, which may 70 form a part of or be included in any suitable transmission, not shown, through which power is imparted to said shaft from the usual motor, not shown. To one end of said shaft is connected a crank-arm 8^a, and connected to said crank-arm is a connecting bar or pitman 9 which is adapted to have an operative connection with the cylinder or tub through the controllable means to be described. 80

Connected with or adapted to be connected to the cylinder or tub 4 is a shaft 10 journaled in any suitable manner in the frame 6, and said shaft has connected thereto a gear wheel or pinion 11. Meshing with said gear wheel is a toothed segment 12 having a pivotal connection with a member 13 connected to or supported by the frame 6. To said segment is connected a pivot member 14 arranged in spaced relation to the axis of 90 the member 13 and on said member 14 is carried a casting 15, forming a bearing member and being formed with a barrel or sleeve-like part 16 and a chambered portion 17. Slidably carried through said barrel or sleeve-like part of said member 15 is a rod or bar 18, its outer end connected with a casting 19 having connected thereto a pivot member 20 to which is connected a lever 21 fulcrumed at 22 to the frame 7. 100 The inner end of the rod or bar 18 has connected thereto a casting 23 having a shank 24 which is pivotally connected with the upper end of the connecting bar or pitman 9. 105

The rod or bar 18 is provided with a plurality of spaced seats or depressions 25 with which coat the ball member 26 located in the casting 15 at the lower end of the chamber 17 in which is carried the spring 27 to normally hold the ball member in contact with the rod or bar 18. As the rod or bar 18 is moved back and forth through the casting 15 the ball member 26 will ride or roll on the surface of said rod or bar, and enter into each seat or depression 25 brought coincident therewith. The lock formed by the ball and seats or depressions to hold the rod or bar in different positions, whereby a variable movement may be imparted to the cylinder or tub, may be felt out by the attendant during the movement of said bar or rod, and very little effort or exertion on the part of the attendant will be required to release the rod or bar and to move it to its two extreme and predetermined positions, one operative and the other inoperative. 115 120 125

When the parts are in operative position the member 20 is in axial coincidence with the axis of the pivot member 13 for the toothed segment, the rod or bar 18 having 130

been moved outwardly bringing the casting 23 on the inner end thereof adjacent the casting 15 on the pivot member 14. In such position of the parts the rod or bar 18 may be oscillated up and down around the pivot member 20, as the connecting or pitman bar 9 is moved up and down, due to the rotation of the crank-arm 8^a, the thrust of said bar 9 being substantially in the direction of the pivot member 14 on the toothed segment and oscillating said segment, resulting in an alternate rotary movement being imparted to the gear wheel or pinion 11 and a like movement being imparted to the cylinder or tub, somewhat as illustrated in Figure 2. When the parts are in inoperative position, that is so far as the movement of the segment 12 and cylinder or tub is concerned, the pivot member 20 is in axial coincidence with the pivot member 14 on said segment and the casting 19 on the outer end of the rod or bar 18 has been moved to a position adjacent the casting 15. In this position of the parts as the connecting bar or pitman 9 is moved up and down the rod or bar 18 will be oscillated but will idle on the pivot member 20, somewhat in the manner shown in Figure 3, and without imparting movement to the segment 12 or the cylinder or tub. The movement of the lever 21 which will bring the member 20 into axial coincidence with the member 14 automatically restores the cylinder or tub to the "normal" or "neutral" position seen in Figure 3.

In addition to the advantage of restoring the cylinder or tub to normal or neutral position and stopping its movement, my improvement has the further advantage of permitting the attendant to move the controlling means to different selective positions between its two extreme and predetermined positions, whereby greater or less movement of the cylinder may be obtained. This is particularly desirable in the handling of coarse and fine fabrics and clothing. With such a controllable means as I have disclosed the movement of the tub may be gradually started and gradually stopped and there is no jerking or jiggling of the tub, as it is brought to a positive stop.

What I claim is:—

1. In a machine of the character described, in combination, a tub mounted to be alternately rotated, gearing arranged to impart alternate rotation to said tub, a lever means for actuating said gearing having a plurality of predetermined fulcrum positions, said means including a controllable means for adjusting the fulcrum point of said actuating means to move the tub or restore it to normal stopped position, and means for holding said lever means at different points between two extreme positions.

2. In a machine of the character described, in combination, a tub mounted to be alter-

nately rotated, gearing arranged to impart alternate rotation to said tub, an operating means, operating connections between said gearing and said operating means, and a controllable means in said connections movable to a plurality of selective positions and adapted to be held in such positions, in certain of such positions the said gearing is effective for tub movement and in one of such positions the gearing is ineffective for tub movement and the tub is restored and held in normal stopped position, means to hold said controllable means in certain of its operating positions, and manually operable means for moving said controllable means.

3. In a machine of the character described, in combination, a tub mounted for movement, gearing arranged to impart movement to said tub, a sleeve like member connected with said gearing, a rod having a slidable rotation in said member, a lever having a connection with one end of said rod for moving the latter alternately to operative and inoperative positions, and during such movement to the latter position bringing the tub to its normal position, an operating mechanism, and operating connections between said rod and said mechanism.

4. In a machine of the character described, in combination, a tub mounted for movement, gearing arranged to impart movement to said tub, including a segment gear member, a sleeve like member connected with said segment gear and in spaced relation to its axis, a pivotally supported rod having a slidable relation in said sleeve like member, and means for moving the axis of the pivot for said rod alternately into axial coincidence with the axis of said segment gear and the axis of said pivot member.

5. In a machine of the character described, in combination, a tub mounted for movement, gearing arranged to impart movement to the tub, including a segment gear, a member connected with said segment gear in spaced relation to its axis, a rod slidably carried through said member and provided with a plurality of spaced indentations, a lever, a member on one end of the rod in pivotal connection with said lever, the axis of which is adapted to be moved alternately into axial coincidence with the axis of the segment gear and the member connected thereto, means to oscillate said rod, and means to engage in the indentations in said rod to hold the rod in different positions.

6. In a machine of the character described, in combination, a tub mounted for movement, gearing arranged to impart movement to the tub, including a segment gear, a driving shaft, operating connections between said shaft and said segment gear, including a member connected to said segment gear in spaced relation to its axis, a rod having a slidable relation with said member, means

connecting the rod and shaft, a lever, and means pivotally connecting said rod with said lever, said pivotal connection of the rod and lever adapted to be moved into axial coincidence with the axis of the segment member to operate the gearing and tub and adapted to be moved into axial coincidence

with the member connected to the segment gear to simultaneously restore the tub to normal position and stop the movement of 10 gearing and tub.

In witness whereof, I have hereunto affixed my hand this 11th day of April, 1923.

BENJAMIN E. GETZ.
